UNITED STATES PATENT OFFICE.

HARRIET L. FORD, OF SEATTLE, WASHINGTON.

LAUNDRY DEVICE.

1,271,149.

Specification of Letters Patent. Patented July 2, 1918.

Application filed November 15, 1916. Serial No. 132,478.

To all whom it may concern:

Be it known that I, HARRIET L. FORD, a citizen of the United States, residing at Seattle, in the county of King and State of 5 Washington, have invented a new and useful Improvement in Laundry Devices, of which the following is a specification.

This invention relates to improvements in laundry devices, and the object of this 10 improvement is to provide a strong, simple, and comparatively inexpensive device that is provided with a handle and has jaws associated therewith that are adapted to grasp a piece of fabric in such a manner that the 15 fabric may be rubbed over a wash board to wash it.

A further object is to provide means that 20 may be operated from a point near the end of the handle to open and close the jaws. 25 The invention consists in the novel construction, adaptation, and combination of parts, as will be more clearly described in the following specification, illustrated in the accompanying drawings, and finally pointed out in the appended claims.

In the well known method of washing clothes by hand on a wash board that is placed in a tub of water, it is necessary for the person who is doing the washing to 30 grasp the clothes with the hands and rub them over the wash board. This often results in the hands being immersed in strong soap suds for long periods of time and in the fingers being rubbed over the wash 35 board and the clothes until the skin is worn off and they are made sore. Moreover, the above method also necessitates a continuous bending of the back, which tires a person very quickly. I have found that by 40 the use of the device herein disclosed the work of rubbing clothes over a wash board may be done very satisfactorily without immersing the hands or rubbing them on the wash board and without bending the back 45 continuously.

In the accompanying drawings, Figure 1 is a view in side elevation of a device embodying this invention. Fig. 2 is a plan view of the same with the handle broken 50 away; Fig. 3 is an enlarged view in cross section substantially on broken line 3, 3 of Fig. 2; Fig. 4 is a view in elevation of the end of the handle showing parts in the position they may assume when the jaws are 55 opened; Fig. 5 is a plan view of the end of the handle, showing the jaw actuating

mechanism in a closed position; and Fig. 6 is a view in front elevation illustrating a modified form of gripping member, certain parts being omitted.

Referring to the drawings throughout which like reference numerals indicate like parts, the numeral 7 indicates a handle adapted to fit within a socket member 8 formed integral with, or rigidly secured to, 60 an arcuate front jaw, member 9.

10 is a rear jaw member secured on a transverse bar 11 that is pivoted in downwardly projecting lugs 12 that are provided on each end of the member 9.

13 is a lever arm that is secured to the movable jaw 10 and projects upwardly through a slot 14 in the top central portion of the jaw member 9, and 15 is an actuating rod that is pivoted to the top end of the 75 lever arm 13 and extends lengthwise of the handle through guides 16 and 17, the guide 17 being in the form of a block that is slideable lengthwise on the handle 7.

18 is a compression spring that is placed 80 on the rod 15 between the block 17 and a knob 19 on the outer end of the rod, and 20 is a fixed pin extending through the rod 15 just below the block 17.

21 is a forked lever member secured to the 85 handle 7 by pivots 22 and articulated by pivot members 23 with two links 24 that are pivotally secured, as at 25, to the sides of the block 17 in such manner that when the lever member is thrown upwardly into the position shown in Fig. 4, the block 17 will be moved downwardly on the handle, and when the lever member is moved downwardly into the position shown in Figs. 1 or 5, the block 90 17 will be moved outwardly on the handle 7, 95 the pivot 23 passing the center line of the pivots 22 and 25 when the lever arm is in the position shown in Fig. 1 and automatically forming a lock.

The jaw member 10 may be moved into 100 the open position shown by broken lines in Fig. 3 by throwing the lever member 21 forward into the position shown in Fig. 4. When the jaws are thus open they may be placed on a piece of fabric 26, as a garment 105 that is to be washed, and the lever member 21 may be pulled backward into the closed position shown in Fig. 1, the jaw 10 closing toward the jaw 9 and tightly clasping the fabric 26 and the spring 18 holding the 110 fabric tightly clasped until the lever member is again thrown forward.

The spring 18 permits the lever member to always be thrown completely down, and the jaws so close with equal firmness on a thin or a bulky piece of fabric, and the pin 20 5 engages the lower end of the block 17 and causes the rod 15 to be moved forwardly therewith to open the jaws when the lever member 21 is thrown forward.

In the device, as shown in Figs. 1 to 5 inclusive, the gripping edges of the jaws are preferably smooth and unbroken; but in Fig. 6 I have shown a modified form wherein the gripping edges of the jaws are serrated or cut away to form tooth-like members 27 that grip the fabric more securely.

Obviously changes in the form of construction of this device may be resorted to without departing from the spirit of the invention or sacrificing any of its advantages.

20 What I claim and desire to protect by Letters Patent is:

1. A device of the class described, comprising jaw members, a handle secured thereto, a slidable member on said handle, a 25 jaw-actuating bar pivotally connected with one of said jaw members and extending lengthwise of said handle through said slid- able member, a knob on the end of said actuating bar, a compression spring interposed

between said knob and the end of said slid- 30 able member, a lever arm pivoted on said handle and links connecting said lever arm with said slidable member.

2. A device of the class described, comprising an arcuate jaw member, a handle se- cured thereto, a slidable block on said handle, a movable jaw member pivoted to said first named jaw member, a lever arm on 35 said movable jaw member, an actuating rod pivoted to said lever arm and extending lengthwise of said handle through said slid- able block, a stop on said rod engageable with the inner end of said block, a knob on the outer end of said rod, a compression 40 spring interposed between said knob and the outer end of said slidable block, a forked lever arm pivoted to said handle, and links connecting said slidable block with said forked lever arms and adapted to move said slidable block lengthwise of said handle 45 when lever arm is moved on its pivot.

Signed by me at Seattle, Washington, this 30th day of Oct. 1916.

HARRIET L. FORD.
